UNITED STATES PATENT OFFICE.

RILEY WHITING, OF BEREAL, OHIO.

IMPROVEMENT IN TRACE-FASTENERS.

Specification forming part of Letters Patent No. 157,111, dated November 24, 1874; application filed August 19, 1874.

To all whom it may concern:

Be it known that I, RILEY WHITING, of Berea, in the county of Cuyahoga and State of Ohio, have invented an Improved Whiffle-tree End, of which the following is a specification:

This invention relates to certain improvements in whiffle-tree ends; and consists of a coupling for securing the end of, or the cockeye on the end of, a harness-tug to the whiffle-tree, the said coupling consisting of a loop or eye formed on the whiffle-tree end, and having a pin pivoted at one side, and lying across said loop for holding the tug or cockeye in said loop. The pin is held down and kept from rattling by means of a spring underneath the rear end, just back of the pivot.

To enable others to fully understand my invention, I will proceed to describe the same by the aid of the accompanying drawing, in which—

Figure 1 is a side elevation, and Fig. 2 is a longitudinal section, of my aforesaid device.

A represents the ferrule portion of a whiffle-tree end, by which it is secured to the end of the whiffle-tree. B is a loop or eye formed on the end through which the cockeye passes. C is a pin pivoted in a chamber formed for that purpose, the outer end lying in a recess in the opposite side of the loop. The rear end of the pin C has a shoulder, under which is placed a spring, D, the upper side of the pin having a projection, E, by which it may be held up by the thumb or finger of one hand

while the tug is being uncoupled with the other.

In order to couple the tug to the whiffle-tree it is only necessary to push the cockeye through the loop which lifts the pin, and when the cockeye is in far enough, the pin flies down in place by the force of the spring, as represented in dotted lines in Fig. 2. This makes a permanent coupling for attaching tugs to whiffle-trees. The tug cannot become detached by any means except by the use of two hands, will not rattle out, and is readily and quickly operated. It is strong and durable, and is equally applicable to the ends of neck-yokes, and may, by changing the form a little, be applied to holding the check-rein on the saddle-tree, to each and all of which I design applying it.

I am aware that it is not new to make whiffle-tree ends or hooks with a loop and spring-tongue, for holding the tug or trace in position, and I do not claim this, broadly, as my invention; but

What I claim as new, and desire to secure by Letters Patent, is—

The whiffle-tree end, composed of the recessed ferrule A and loop B, pivoted tongue C, having projection E, and spring D, combined to operate substantially as and for the purpose specified.

RILEY WHITING.
